US0D1060029S

(12) **United States Design Patent** (10) Patent No.: **US D1,060,029 S**
(45) Date of Patent: ** Feb. 4, 2025

- (54) **CARTON WITH TAMPER EVIDENT FEATURE**
- (71) Applicant: **Inno-Pak, LLC**, Delaware, OH (US)
- (72) Inventor: **Steven A. Mayer**, Indianapolis, IN (US)
- (73) Assignee: **Inno-Pak, LLC**, Delaware, OH (US)
- (**) Term: **15 Years**
- (21) Appl. No.: **29/828,418**
- (22) Filed: **Feb. 25, 2022**
- (51) LOC (15) Cl. **09-03**
- (52) U.S. Cl. **USPC D9/433; D9/416; D9/431**
- (58) **Field of Classification Search**
